UNITED STATES PATENT OFFICE.

MAX GERNSHYM, OF BROOKLYN, NEW YORK.

CIRCULAR-KNITTING MACHINE.

SPECIFICATION forming part of Letters Patent No. 462,546, dated November 3, 1891.

Application filed June 17, 1891. Serial No. 396,562. (No model.)

To all whom it may concern:

Be it known that I, MAX GERNSHYM, of Brooklyn, in the county of Kings and State of New York, have invented new and useful Im-

5 provements in Circular-Knitting Machines, of which the following is a full, clear, and exact description.

The invention relates to circular-knitting machines having plate-needles and cylinder-10 needles for producing ribbed tubular fabrics.

The object of the invention is to provide certain new and useful improvements in circular-knitting machines, whereby part of the tubular fabric produced is formed with a figured design according to a predetermined 15 pattern, while the rest of the fabric is knitted in the usual manner in plain ribs with Cardigan or other stitch.

The invention consists in forming either 20 the cylinder or plate, or both, in sections, of which one is shifted to change the relative position of part of the cylinder and plate needles.

The invention further consists of pattern-25 wheels governing the movement of the movable section to reproduce on the fabric the pattern represented by the pattern-wheel.

The invention also consists of certain parts 30 and details and combinations of the same, as will be hereinafter described, and then pointed out in the claims.

Reference is to be had to the accompanying drawings, forming a part of this specification, in which similar letters of reference indicate 35 corresponding parts in all the figures.

Figure 1 is a plan view of the improvement as applied, detailed parts of the ordinary knitting-machine being omitted. Fig. 2 is a 40 sectional side elevation of the same on the line $x-x$ in Fig. 1. Fig. 3 is a transverse section of the same on the line $y-y$ in Fig. 1. Fig. 4 is an inverted plan view of the improvement, and Fig. 5 is a side elevation of the 45 fabric produced.

The improved knitting-machine is of the ordinary circular type and is provided with the usual bed-plate A, mounted on suitable legs A' and carrying in its middle part the needle-plate B, on the top of which are fitted 50 to slide the plate-needles C, receiving their horizontal sliding motion in the usual manner from the cam D, mounted to revolve and

provided with gear-teeth D' in mesh with the gear-wheel E', secured on the main shaft E, mounted to turn in suitable bearings on the 55 bed-plate A.

The needle-plate B is made in two sections B' and B², of which the section B' is fixed, while the section B² is fitted to slide, one or two needles being omitted at the adjoining 60 ends of the said sections to permit sufficient movement of the section B². The cam D for the plate-needles C is provided with the usual spider D², mounted to turn on the spindle F, on the lower end of which is mounted to turn 65 the cam-cylinder G, surrounded by the needle-cylinder H, carrying the vertical or cylinder needles I, operating in conjunction with the plate-needles C to produce the fabric. It will be seen that when the movable section 70 B² of the needle-plate is shifted its needles change their position relative to the vertical or cylinder needles extending along the inner edge of the said movable section B². Thus by varying the distance the section B² is 75 shifted relative to the vertical or cylinder needles I, a different design or pattern-work may be produced in that part of the fabric knitted by the needles contained in the section B² and the corresponding vertical needles. The section B² may be shifted, so that 80 one of its needles moves the distance between two, three, four, or more vertical needles I to vary the design, as may be desired. A variation may also be produced by forming the 85 needle-cylinder H of two sections H' and H², of which the section H' is fixed and the other section H² is shifted circularly on the cylinder G. The section H² is arranged in line with the section B², so that the two sections, 90 when shifted in opposite directions, shift the relative position of their needles to produce certain pattern-work. A like result may be produced by shifting the section H² only, the section B² remaining stationary or forming an 95 integral part of the other section B', as in ordinary knitting-machines. It is understood that this shifting of the section B² or H², or both, at the same time takes place, preferably, at every revolution of the cylinder G and the 100 cam D, and at the time the needles C are in their innermost position and the needles I in their lowermost position. The cylinder G is carried along by a pin D³, engaging a projec-

tion on the said cylinder and held removably in the spider D² of the cam D. (See Fig. 2.)

The segmental section B² of the needle-plate B is held in place by a series of plates 5 J, fastened to or forming integral parts of the bed-plate A, as plainly illustrated in Fig. 4. Each plate projects under the segmental section B², and is provided with a slot J', through which passes a screw J², screwing in the section B². The plates J thus form a bearing with the bed-plate A for the movable section B², and the slots J' permit movement of the screws J², carried by the section B². The shifting of the movable section B² is accomplished by means of a lever K, fulcrumed at K' on the bed-plate A and provided at its inner end with a recess and set-screws K², engaging a projection K³ extending downward from the movable section B². The outer end 15 of the lever K carries two pins or friction-rollers K⁴, engaging opposite faces of a pattern-wheel L, secured on a shaft N, mounted to turn in suitable bearings held in brackets projecting from the bed-plate A.

20 The shaft N carries a ratchet-wheel O, engaged by a pawl O', pivoted on a lever O², fulcrumed loosely on the shaft N, and carrying at its free end a friction-roller O³, engaging a cam P, fastened to the cam D for the plate-needles. Thus when the cam D rotates the cam P imparts a swinging motion to the lever O², so that its pawl O', engaging the ratchet-wheel O, turns the latter, and consequently the shaft N, carrying the pattern-wheel L. The latter is shaped on its faces according to the movement desired to be given the section B², so that the rotation of the said pattern-wheel L imparts a swinging motion to the lever K, which, by engaging the 30 section B², shifts the latter forward or backward to change the relative positions of the plate-needles carried by the section B² relative to the corresponding vertical or cylinder needles operating in conjunction with the 35 plate-needles carried by section B².

The cam P is arranged opposite that part of the cam-groove in the cam D by which the inward-sliding motion of the needle C is accomplished. (See Fig. 1.) If the section H² of 40 the needle-cylinder H is shifted for changing the design of part of the fabric, then a similar device is employed as above described, in reference to the section B²—that is, a lever Q for shifting the said section and a pattern-wheel L' for operating the said lever Q.

The lever Q is fulcrumed at Q' on the bed-plate A, and carries at its outer end pins or friction-rollers Q², engaging opposite faces of the pattern-wheel L'. The inner end of 45 the lever Q carries a grooved friction-roller Q³, engaging a vertical rib R', formed in the ring R, attached to the section H² of the needle-cylinder H. It is understood that the connection between the lever Q and the section H² is made in this manner, so that the fabric can pass down over the said needle-cylinder—that is, between the friction-roller

5 Q³ and the ring R, at the same time permitting the lever Q to shift the section H² whenever the said lever is actuated from the pattern-wheel L'. 70

It is understood that both sections B² and H² can be operated simultaneously, but in opposite directions, by their levers K and Q and the pattern-wheels L and L', respectively. Either of the levers K or Q, however, may be disconnected from its respective pattern-wheel, so that only one lever at a time operates its respective section to produce a figured or pattern part on the fabric. It will 80 further be seen that instead of making either the needle-plate or the needle-cylinder each in two sections, as above described, and illustrated in the drawings, each may be made in three or more sections to produce figured or 85 pattern work on different parts of the fabric.

It is understood that in case more than two sections are employed several may be movable and the rest fixed, according to the work designed to be finished on the machines. 90 The fixed and movable sections are then preferably arranged alternately.

As illustrated in Fig. 5, the fabric produced is a Cardigan jacket, which is made in tubular form by the knitting-machine, then the 95 front is cut open, then the sleeves are inserted, and the same attached in the usual manner; but the front f of the cardigan has a design or pattern work, while the rear or back part is of the ordinary ribbed style. 100

I am aware that circular-knitting machines have been constructed in which the entire needle-cylinder is shogged for forming a circular commencing course or a circular border on the fabric, and I am further aware that 105 straight-knitting machines provided with sections capable of being shogged have been in use; but such construction and the results obtained thereby are foreign to my invention, and I do not claim the same. 110

The fabric produced by this machine forms the subject-matter of a separate application filed by me under date of July 22, 1891, Serial No. 400,294.

Having thus described my invention, I 115 claim as new and desire to secure by Letters Patent—

1. A circular-knitting machine provided with a set of plate-needles, a set of cylinder-needles, and means for circularly shifting 120 part of the said plate-needles and part of the said cylinder-needles, substantially as shown and described.

2. A circular-knitting machine provided with a set of cylinder-needles, and means for 125 circularly shifting part of the said set of cylinder-needles, substantially as shown and described.

3. A circular-knitting machine provided with a set of plate-needles, and means for 130 circularly shifting part of the said plate-needles, substantially as shown and described.

4. A circular-knitting machine provided with a circular needle-plate composed of fixed

and movable segmental sections, substantially as shown and described.

5. A circular - knitting machine provided with a circular needle-plate composed of a fixed segmental section and a movable section, and means for circularly shifting the movable section, substantially as shown and described.

6. A circular - knitting machine provided with a needle - cylinder made of fixed and movable segmental sections, substantially as shown and described.

7. A circular - knitting machine provided with a needle-cylinder composed of fixed and movable segmental sections, and means for circularly shifting the said movable sections, substantially as shown and described.

8. A circular - knitting machine provided with a needle-cylinder made in fixed and circularly-movable sections, and a needle-plate composed of a fixed section and a section circularly movable relative to the said movable needle-cylinder section, substantially as shown and described.

25 9. In a circular-knitting machine, the combination, with a needle - plate composed of fixed and movable segmental sections, of a lever engaging the said movable section to move the same circularly, and a pattern-wheel for actuating the said lever, substantially as shown and described.

30 10. In a circular-knitting machine, the combination, with a needle-plate composed of a fixed section and a circularly-movable section, of a lever engaging the said movable section, a pattern-wheel for actuating the said lever, a plate-needle cam, and means for actuating the said pattern-wheel from the said cam, substantially as shown and described.

11. In a circular-knitting machine, the combination, with the cylinder-needles, the needle-cylinder, and means for operating the cylinder-needles, of the cam for the plate-needles, the needle-plate made in sections, of which one is fixed and the other movable, and means for imparting motion to the movable section, substantially as shown and described.

40 12. In a circular-knitting machine, the combination, with the cylinder-needles, the needle-cylinder, and means for actuating the cylinder-needles, of the cam for the plate-needles, the needle-plate made in fixed and movable segmental sections, and means, substantially as described, for imparting motion to the said movable section, comprising a lever connected 50 with the said movable section, and a pattern-wheel for actuating the said lever and receiving its motion from the said cam for the plate-needles, substantially as shown and described.

55 13. In a circular-knitting machine, the combination, with the cylinder-needles, the needle-cylinder, and means for actuating the cylinder-needles, of the cam for the plate-needles, the needle-plate made in fixed and movable segmental sections, means, substantially as 60 described, for imparting motion to the said movable section, comprising a lever connected with the said movable section, and a pattern-wheel for actuating the said lever and receiving its motion from the said cam for the plate-needles, and intermediate mechanism for connecting the said cam for the plate - needles with the said pattern-wheel, substantially as 65 shown and described.
